PROCESS OF TREATING HYDROCARBON
OIL

Sturgis W. Darling, Houston, Tex., assignor, by
mesne assignments, to Texaco Development
Corporation, New York, N. Y., a corporation of
Delaware

Application June 15, 1937, Serial No. 148,269

14 Claims. (Cl. 196—48)

This invention relates to the art of producing gasoline-like products or relatively low-boiling hydrocarbons from relatively high-boiling hydrocarbons.

According to this invention a relatively clean oil stock, preferably a condensate oil obtained by fractionation of vapors in a bubble tower, is passed through the first portion of a cracking zone which preferably extends through the radiant section of a furnace wherein the oil is maintained under high-temperature and high-pressure conditions to effect part or all of the desired conversion thereof. The heated oil, after passing through this portion of the cracking zone, is divided into two streams, one stream being passed to a coking zone, such as an enlarged coke still to supply the heat required to decompose heavy oil introduced into the coking zone to a solid coke-like mass. The other stream is mixed with a heavy oil containing reflux condensate and unvaporized constituents of a relatively heavy oil, such as, a reduced crude oil charge, and the combined stream is passed through the latter portion of the cracking zone which preferably extends through the convection section of the furnace to effect viscosity-breaking of the heavy oil and further cracking of the clean oil. The stream of combined cracked products leaving the cracking zone is passed into a separating zone or evaporator to separate vapors and unvaporized oil, the latter being passed to a flash or vaporizing zone preferably maintained under reduced pressure to vaporize volatile constituents therefrom. All or part of the remaining unvaporized oil or tar residue is passed to the coke still where it is reduced to coke by the heat derived from the stream of oil from the cracking zone in the radiant section of the furnace, as above mentioned. Fresh charging oil for the process, such as reduced crude oil, preheated in any suitable manner, is contacted with the hot vapors from the flash zone and evaporator to form the heavy oil above mentioned which contains reflux condensate and unvaporized constituents of the crude oil. The vapors remaining uncondensed after being contacted with fresh oil are fractionated to separate light motor fuels, such as gasoline, from insufficiently cracked products, such as reflux condensate which is subjected to cracking conditions.

Other advantages and features of the invention will be hereinafter given in the detailed description of the invention in connection with the drawing which shows a flow diagram of ap-

paratus adapted for practicing the methods of this invention.

Referring now to the drawing, the reference character 10 designates a furnace or heater housing a cracking zone in the form of a coil 12. The cracking zone 12 extends, for example, through the radiant section 14 and the hottest part of convection section 16 of the furnace 10. Clean oil, such as reflux condensate obtained in the process as later described, is passed through line 18 by the pump 20 into the preheating coil 22 positioned in the cooler portion of the convection section 16 of the furnace 10. The preheated clean oil then passes through line 24 and through the first portion of the cracking zone 15 which extends through the radiant section 14 of the furnace 10 where it is subjected to high-temperature and high-pressure conditions to bring about the desired conversion. The oil stream leaving the first part of the cracking zone is subdivided into two streams, one stream being passed through a line 26 having a pressure-reducing valve 27 into the coke still 28 in order to supply the heat required therein to crack the tar residue within the coke still to a coke-like mass. The other stream is passed through line 30 and is mixed with a heavy oil which contains relatively heavy reflux condensate and heavy unvaporized liquid constituents of the charge introduced into the process, as will be later described, passing through line 32 by means of pump 33. The lines 26 and 30 are provided with valves to permit controlling the amounts of cracked products being passed through the lines. The combined stream is passed through the latter portion of the cracking zone 12 which is positioned in or which extends through the convection section 16 of the furnace 10. In this latter portion of the cracking zone the introduced heavy oil is subjected to mild cracking, such as a viscosity-breaking treatment, and the oil stream leaving the first part of the cracking zone through line 30 and admixed therewith is subjected to further cracking.

The stream of cracked products leaving the latter portion of the cracking zone 12 is passed through line 34 having a pressure-reducing valve 36 into the evaporator or separating zone 38 of the combined evaporator and fractionating tower 40. Before passing the stream of cracked products into the evaporator 38, a quench oil may be introduced into line 34 as at 42, if desired. Due to the reduction in pressure on the heated oil, there is a separation into vapors, which pass upwardly in the evaporator, and a cracked resi-

due which is collected in the bottom of the evaporator 38. The cracked residue is passed through line 46 having a pressure-reducing valve 48 into the flash zone 49 of the combined fractionator 5 and crude flash tower 50 maintained at a lower pressure than the evaporator 38. Due to the reduction in pressure, there is a further vaporization of the unvaporized liquid or residue withdrawn from the evaporator 38, and the vapors 10 pass upwardly in the flash zone 49 of the combined fractionator and crude flash tower 50. The remaining unvaporized cracked residue or tar is collected in the bottom of the flash zone 49. All or a portion of the cracked tar residue 15 may be passed through line 51 into the coke still 28 where the tar residue is subjected to further cracking by mixture with a portion of the stream of cracked products leaving the first portion of the cracking zone 12 through line 26, as hereinbefore described. If the coke drum 28 is maintained at about the same or higher pressure as the tower 50, a pump 52 is used to force the cracked residue into the drum 28.

Preferably, the cracked tar residue from the 25 flash zone 49 is mixed with the stream of cracked products in line 26 before such stream is introduced into the coke still or drum 28 in order to raise the temperature of the cracked residue to a cracking temperature prior to entering the coke 30 drum to thereby facilitate vaporization of the lighter constituents and decomposition of the tar residue to coke thereby obtaining an increase in the yield of light products from the cracked residue. However, the cracked tar residue from flash 35 zone 49 may be passed directly to the coke still 28, or a part of the cracked tar residue may be passed directly into the coke still and another portion mixed with the stream in line 26 before passing to the coke still 28. Two or more coke 40 stills may be provided so that one still can be in use while another still is being cleaned.

The vapors from the top of the coke still 28 are passed through line 53 into the lower portion of the fractionating section 54 of the combined fractionator and crude flash tower 50. Fresh charging stock for the process, such as reduced crude oil, preferably preheated, is passed through line 58 by means of pump 60 and is introduced into the upper portion of the fractionating section 54 45 of the combined fractionator and crude flash tower 50. The reduced crude oil charge flows downwardly in the fractionating section 54 countercurrent to the hot vapors rising from the flash zone 49 and the hot vapors passing through line 53 from the coke still 28, as hereinbefore described. In this way intimate contact between vapors and liquid oil takes place resulting in condensation of heavier constituents of the vapors and vaporization of lighter constituents contained in the charge oil. The vapors leaving the 55 combined fractionator and crude flash tower 50 are passed through line 62. The heavy reflux condensate and unvaporized reduced crude oil are collected as liquid at the bottom of the fractionating section 54 in the trap-out tray 66 provided with a hood 68. The liquid collected on the trap-out tray 66 is passed through line 70 and is forced into the upper portion of the fractionating section 16 of the combined evaporator and fractionating tower 40 by means of pump 72. In the fractionating section 16 the heavy reflux condensate and unvaporized reduced crude oil are intimately contacted with the hot cracked vapors rising from the evaporator or separating zone 38, and in this 60 way there is a partial condensation of heavy con-

stituents contained in the vapors and additional vaporization of some of the unvaporized reduced crude oil. The reflux condensate and unvaporized reduced crude oil are collected at the bottom of the fractionating section 76 on trap-out tray 5 78 provided with a hood 80. This liquid which collects on the trap-out tray 78 is the heavy oil above mentioned which is pumped through line 32 and mixed with one portion of the sub-divided stream leaving the first portion of the cracking 10 zone 12 through line 30, the mixture being passed through the latter portion of the cracking zone 12 extending through the convection section of the furnace.

The vapors leaving the top of the combined 15 evaporator and fractionating tower 40 are passed through line 84 into the bottom portion of a secondary fractionating zone, such as a bubble tower 86. The vapors introduced into the secondary fractionating zone 86 through line 84 pass upwardly therein and are fractionated to condense insufficiently cracked products as reflux condensate which collects in the bottom of the secondary fractionating zone 86 and forms the clean 20 oil which is passed through line 88 into the cracking zone or coil 12 extending through the radiant section 14 of the furnace 10. A cooling coil 87 in the upper part of the secondary fractionating zone 86 and other methods of refluxing may be used as will be later explained. The vapors of 25 the desired end point pass from the secondary fractionating zone 86 through line 88 and then through a condenser 90, the distillate being collected in a reservoir or collecting drum 92 having a gas outlet 94 and a liquid outlet 96. The distillate which is drawn off through line 96 is a motor fuel of the nature of gasoline. A part of the gasoline collected in the collecting drum 92 30 may be passed through line 98 by pump 100 into the upper portion of the secondary fractionating 35 zone 86 to act as reflux liquid.

The vapors leaving the top of the combined fractionator and crude flash tower 50 through line 62 may be fractionated in tower 86, but they are preferably separately fractionated and a part 45 thereof used as reflux in the secondary fractionating zone 86. The vapors are passed through line 104 into about the middle portion of a gas oil-naphtha fractionating tower 106 to separate naphtha vapors from insufficiently cracked products as reflux condensate. As the vapors pass upwardly in the fractionating tower 106 they are fractionated to condense insufficiently cracked products and the desired naphtha vapors pass through line 108 and condenser 110 wherein they 50 are condensed. The thus obtained condensed naphtha and lighter gaseous hydrocarbons are pumped by means of pump 112 into the lower portion of the secondary fractionating zone 86 55 where the naphtha is mixed with and retained to some extent by the gas oil or reflux condensate and then passed through the cracking zone 12. By mixing the naphtha with the recycle condensate and passing the mixture through the cracking zone 12 reforming of the naphtha is 60 accomplished along with cracking of the gas oil. The gas oil collecting at the bottom of the fractionating tower 106 is forced through line 116 and cooler 118 by pump 120, and a part thereof may be passed through line 122 into the upper portion 65 of the secondary fractionating zone 86 to act as reflux liquid, and the rest of the cooled liquid may be passed through line 124 into the top of the fractionating tower 106 to act as reflux liquid 70 therein. Valves are provided in lines 104 and 108 75

to permit by-passing of the fractionating tower 106 through line 126 whereby the vapors are condensed in condenser 110 and the condensed oil is passed to the bottom of fractionator 86 by pump 112.

In a typical operation contemplated by this invention a reduced crude oil stock or similar heavy oil stock preferably preheated to about 400° to 475° F. in any suitable way is introduced 10 into the fractionating section 54 of the combined fractionator and crude flash tower 50. The pressure in the combined fractionator and crude flash tower 50 is maintained at about 25 to 125 pounds per square inch. The introduced hot reduced 15 crude oil is contacted in the fractionating section 54 with hot vapors rising from the flash zone 49 and with hot vapors coming from the coke still 28 through line 53. In this way some of the vapors in the fractionating section 54 are condensed to 20 form heavy reflux condensate, and the lighter constituents of the reduced crude oil are vaporized. A mixture of unvaporized crude oil stock and heavy reflux condensate is collected in the trap-out tray 66 at the bottom of the fractionating section 54, and this mixture is withdrawn at 25 a temperature of about 650°-700° F., preferably, about 675° F. and forced into the fractionating section 76 of the combined evaporator and fractionating zone 40 by means of the pump 72. The combined evaporator and fractionating zone 40 is maintained at a pressure of about 100 to 400 pounds per square inch.

The mixture introduced into the fractionating section 76 comes in contact with hot vapors rising 30 from the evaporator or separating zone 38 of the combined evaporator and fractionating zone 40 to cause vaporization of some of the liquid mixture. At the same time some of the vapors rising from the evaporator or separating zone 38 are condensed. The vapors leaving the combined 35 evaporator and fractionating zone or tower 40 are passed through line 84 into the bottom of the secondary fractionating zone 86 wherein they are fractionated. The light products having the desired end point are taken off through line 88, 40 condensed and collected in drum 92. During fractionation reflux condensate containing insufficiently cracked products collects at the bottom of the bubble tower or secondary fractionating zone 86, and this condensate is the clean oil or recycle gas oil stock which is passed through 45 line 18 and through the cracking zone 12.

The condensate from the bottom of the secondary fractionating zone 86 may be preheated by 50 passing it through a preheater coil 22 extending through the cooler portion of the convection section 16 of the furnace 10. The preheated oil is then passed through the first portion of the cracking zone 12 extending through the radiant section 14 of the furnace where it is subjected to a cracking temperature of about 900° to 1100° F., preferably about 990° F., and a pressure between about 200 and 1000 pounds per square inch. The cracked products leaving the first portion of 55 the cracking zone 12 are subdivided into two streams, one stream being passed through line 26 to the coke still 28, while the other stream is passed through line 30 and mixed with the heavy oil passing through line 32. The unvaporized 60 crude oil and reflux condensate collecting at the bottom of the fractionating section 76 of the combined evaporator and fractionator 40 are collected in trap-out tray 78, and this mixture constitutes the heavy oil which is passed through line 70 75 32 and through the latter portion of the cracking

zone or coil 12 extending through the convection section 16 of the furnace 10. The heavy oil is at a temperature of about 770°-860° F. preferably about 840° F.

Before passing this heavy oil through the cracking zone 12, it is mixed with a portion of the cracked products leaving the first part of the cracking zone through line 30 as above mentioned, and by this admixture and with heat applied exteriorly to the cracking zone 12, the temperature of the heavy oil is raised to a cracking temperature of about 800° to 975° F., preferably about 900° F., while under a pressure between about 200 and 1000 pounds per square inch to effect a mild cracking of the heavy oil. After the 10 heavy oil is mixed with the divided stream passing through line 30 the combined stream is passed through the latter portion of the cracking zone 12 extending through the convection section 16 of the furnace 10 where further cracking of the 15 clean oil takes place, and the hydrocarbons are converted into low-boiling hydrocarbons within the gasoline-boiling range having an excellent 20 anti-knock quality. During its passage through the latter portion of the cracking zone 12 the 25 heavy oil in the combined stream is subjected to a mild cracking or viscosity-breaking operation thereby forming lower boiling products most of which are recovered as reflux condensate to be subjected to cracking.

The cracked residue from the evaporator or separating zone 38 in the combined evaporator and fractionating tower 40 at a temperature of about 770° to 860° F., preferably about 840° F., is passed into the flash zone 49 of the combined 30 fractionator and crude flash tower 50 which is under less pressure than the combined evaporator and fractionating tower 40, and some flash distillation or vaporization is obtained. The hot vapors which are released in the evaporator or separating zone 38 and in the flash zone 49 are passed upwardly to contact with the hot reduced crude oil, as hereinbefore stated. The cracked tar residue from the bottom of the flash zone 49 is at a temperature of about 700° F. or above. All 35 or only a portion of the cracked tar residue is passed to the coke still 28 through line 51. A part of the cracked tar residue may be withdrawn from the bottom of the flash zone 49 and used as fuel oil. The cracked tar residue from the bottom of flash zone 49 passing through line 51 is 40 preferably mixed with a stream of cracked products leaving the first portion of the cracking zone 12 through line 26 before it is introduced into the coke still 28, but the tar residue may be introduced directly into the coke still 28 or a part thereof may be mixed with the stream of cracked products passing through line 26 and the rest passed directly into the coke still. This stream of cracked products is at a high temperature about 45 900°-1100° F., preferably about 990° F., and is utilized to raise the tar residue to a coking temperature and to further crack the tar residue to obtain an increased yield of gasoline or other light 50 hydrocarbon products. The temperature of the coke still 28 is maintained at about 830°-900° F., 55 preferably about 880° F.

The pressure in the coke still 28 preferably is lower than the pressure in the cracking zone 12, and, therefore, some flash distillation or vaporization of the cracked products is obtained in the coke still. A part of the tar residue from the flash zone 49 may be used as fuel oil, or all of the tar residue may be used to produce coke. It will be observed that a part of the stream of 75

cracked products from the first portion of the cracking zone 12 was diverted to the coke still 28 through line 26 before the heavy oil was injected into the latter portion of the cracking zone 12 through line 32 so as to obtain a stream of cracked products having a high temperature for cracking the tar residue.

The vapors from the coke still 28 are passed through line 53 into the lower portion of the fractionating section 54 of the combined fractionator and crude flash tower 50 below the point of introduction of the hot reduced crude oil charge which is introduced through line 58 into the fractionating section 54 of the combined fractionating and flash tower 50. These vapors from the coke still contain cracked naphtha vapors which are combined with the gas oil for reforming as will be presently described. Some of the vapors are fractionated in the fractionating section 54 and the vapors passing overhead through line 62 are condensed and the condensate is introduced by pump 112 or through line 122 into the secondary fractionating zone 86 to be added to the gas oil condensate for recycling through cracking zone 12 and reforming of the cracked naphtha.

The vapors from the top of the combined fractionator and crude flash tower 50 may be condensed to recover a hydrocarbon product, or they may be passed to the gas-oil naphtha fractionating tower 106. The liquid from the bottom of the fractionating tower 106 may be cooled and passed through line 122 to the top of the secondary fractionating zone 86 as gas oil reflux, or a part of the liquid may be passed through line 124 and used as reflux liquid for the fractionating tower 106. The vapors coming from the top of the fractionating tower 106 are, preferably, condensed and passed to the lower portion of the secondary fractionating zone 86 to be added to the condensate oil therein. The vapors leaving the top of the fractionating tower 106 contain naphtha constituents. These vapors are condensed by passing through condenser 110 and the condensate is added to the gas oil or condensate oil in the bottom of the secondary fractionating zone 86 for reforming the naphtha constituents when the condensate oil is recycled through line 18 and passed through the cracking zone 12.

The vapors from the secondary fractionating zone 86 may be condensed and the liquid collected and treated in the usual manner to produce gasoline or the like.

While the primary and secondary fractionating zones have been shown in the drawing in separate towers, it is to be clearly understood that these zones can be located in a single tower; also the evaporator and flash zone, while shown in the drawing as parts of a combined fractionator and crude flash tower, and a combined evaporator and fractionating tower, respectively, can be constructed and used as separate apparatus as will be apparent to one skilled in the art.

While a particular embodiment of the invention has been described it is to be expressly understood that the invention is not restricted thereto, and various modifications and adaptations thereof may be made without departing from the spirit of the invention.

I claim:

1. In a process for converting higher-boiling hydrocarbons into lower-boiling ones, in which oil is passed through a cracking zone and then into a separating zone to separate vapors from

the cracked residue, the vapors being passed through primary and secondary fractionating zones and the cracked residue being passed to a flash zone to produce further vaporization thereof, the vapors leaving said second fractionating zone being condensed and collected as a hydrocarbon product having the desired boiling range, the steps which comprise passing condensate oil from the secondary fractionating zone to the cracking zone wherein it is maintained under high-temperature and high-pressure conditions to produce conversion of the condensate oil, contacting a relatively heavy oil stock with the hot vapors from the flash zone to vaporize some of the lighter constituents of the heavy oil and to condense some of the vapors to form reflux condensate and collecting reflux condensate and unvaporized constituents of the heavy oil and passing them to the primary fractionating zone where further contact with hot vapors occurs, collecting reflux condensate and unvaporized liquid constituents of the heavy oil in the primary fractionating zone and admixing such reflux condensate and unvaporized heavy oil with the cracked products passing through the latter part of the cracking zone to raise the temperature of the admixed condensate and unvaporized heavy oil to a cracking temperature, passing such admixture through the latter part of the cracking zone to effect conversion thereof and then passing such mixture to the separating zone to separate hot vapors which are passed to the primary fractionating zone.

2. A process for converting higher boiling hydrocarbons into lower boiling hydrocarbons, which comprises contacting reduced crude oil stock with hot hydrocarbon vapors to vaporize some of the reduced crude oil stock and to condense some of the hot vapors as heavy reflux condensate, collecting the heavy reflux condensate and unvaporized crude oil and passing them to a primary fractionating zone wherein they flow downwardly and contact hot vapors therein, passing the vapors from the primary fractionating zone to a secondary fractionating zone wherein they are fractionated to separate condensate oil from a hydrocarbon product containing lower boiling hydrocarbons, collecting the condensate oil from the secondary fractionating zone and passing it as a stream through the first portion of a cracking zone in the radiant section of a furnace, collecting reflux condensate and unvaporized crude fraction in the primary fractionating zone and admixing such condensate and unvaporized crude fraction with the first-mentioned stream leaving the cracking zone in the radiant section of the furnace to form a combined stream and passing the combined stream through the latter portion of the cracking zone in the convection section of the furnace, passing the treated and cracked products from the cracking zone to a separating zone to obtain separation of vapors from cracked residue, passing the vapors to said primary fractionating zone, passing the cracked residue to a flash zone maintained at a lower pressure to obtain flash distillation into vapors and tar residue, passing the tar residue from the flash zone to a coking zone and diverting a portion of the stream of cracked products from the cracking zone in the radiant section of the furnace to the coking zone to obtain further cracking of the tar residue therein, the stream being diverted before the introduction of the reflux condensate and liquid from the primary fractionating zone, and passing the vapors from the

coking zone into contact with the reduced crude oil to condense a portion thereof which forms part of the reflux condensate passed to the top of the primary fractionating zone.

5. 3. A process for converting high boiling hydrocarbons into low boiling hydrocarbons which comprises intimately contacting relatively heavy charging oil stock with hot vapors to vaporize some of the heavy oil stock and collecting the unvaporized heavy oil, subjecting the vapors to fractionation to condense heavy constituents therefrom, condensing the remaining vapors and collecting the distillate as a relatively low boiling fraction, subjecting the condensed heavy constituents to elevated temperature and superatmospheric pressure to effect conversion thereof into lower boiling products, dividing the products of conversion into at least two portions, admixing the unvaporized heavy oil with one of the divided portions to supply heat to the heavy oil and to effect cracking of the heavy oil, separating the products of conversion from the admixed stream into hot vapors and unvaporized liquid constituents, using the last-mentioned hot vapors as the vapors for contacting the relatively heavy charging oil stock, passing the unvaporized liquid constituents to an enlarged zone wherein they are subjected to further conversion, passing another of the divided portions into the enlarged zone to supply heat to the unvaporized liquid constituents in the enlarged zone to subject them to further conversion.

4. A process for converting higher-boiling hydrocarbons into lower-boiling hydrocarbons which comprises passing oil through a cracking zone wherein it is maintained under high-temperature and high-pressure conditions to effect the desired cracking, passing a portion of the stream of cracked products into a separating zone to separate hot vapors from a cracked residue, passing cracked residue thus obtained to a flash zone under a lower pressure for further separation into hot vapors and a tar residue, withdrawing the tar residue and passing it to a coking zone, contacting relatively heavy hydrocarbon oil with the hot vapors from the flash zone to vaporize part of the heavy oil, collecting the unvaporized portions of the heavy oil and contacting them with the hot vapors from the separating zone to vaporize the lighter constituents thereof and condense some of the heavy constituents from the vapors, and further treating the separated lighter constituents to separate a relatively light hydrocarbon fraction therefrom, collecting and admixing the unvaporized portions of the heavy oil with the portion of the stream of cracked products passing to the separating zone to thereby raise the heavy oil to cracking temperature and effect cracking thereof, and passing another portion of the stream of hot cracked products from the cracking zone to the coking zone to effect cracking of the tar residue introduced into the coking zone.

5. A process for converting higher boiling hydrocarbons into lower boiling hydrocarbons, which comprises contacting relatively heavy oil stock with hot vapors in a fractionating zone to vaporize some of the heavy oil and condense some of the vapors as heavy reflux condensate, collecting the heavy reflux condensate and unvaporized constituents of the heavy oil stock and passing them to a primary fractionating zone in contact with hot vapors therein to vaporize some of the reflux condensate and unvaporized constituents of the heavy oil stock and to condense some of the hot vapors, passing the vapors from the primary fractionating zone to a cracking zone wherein they are cracked to raise the temperature of the introduced reflux condensate and unvaporized constituents of the heavy oil to a cracking temperature and effect cracking thereof, and passing the commingled treated and cracked products to a separating zone to separate hot

5. mary fractionating zone to a secondary fractionating zone wherein they are fractionated to separate condensate oil from lighter hydrocarbon vapors which are condensed and the distillate separated as a desired product, collecting the condensate oil from the secondary fractionating zone and passing it through a portion of a cracking zone wherein it is maintained under high temperature and high pressure conditions to effect the desired conversion, collecting reflux condensate and unvaporized constituents of the heavy oil in the primary fractionating zone and passing them through another portion of the cracking zone after the reflux condensate and unvaporized constituents of the heavy oil are commingled with cracked products coming from the first mentioned portion of the cracking zone, and passing the commingled treated and cracked products from the cracking zone to a separating zone to separate hot vapors from cracked residue and passing such hot vapors into the primary fractionating zone to supply hot vapors thereto, directing cracked residue from said separating zone to a flash zone wherein separation of vapors from tar residue takes place under a lower pressure and passing resultant separated vapors to the first-mentioned fractionating zone, passing the vapors from said first mentioned fractionating zone to a fractionating tower to obtain gas-oil and naphtha fractions, introducing the naphtha fraction into the bottom portion of the secondary fractionating zone and introducing the gas-oil fraction into the top portion of the secondary fractionating zone to effect condensation of heavy constituents of the vapors therein which are added to the condensate oil in the secondary fractionating zone.

6. A process as defined in claim 5 wherein tar residue from the flash zone is passed to a coking zone and at least a portion of the cracked products from the first mentioned portion of said cracking zone is diverted to said coking zone to crack the tar residue.

7. A process for converting higher boiling hydrocarbons into lower boiling hydrocarbons, which comprises introducing relatively heavy oil stock into the fractionating section of a flash tower in contact with hot vapors therein to vaporize some of the heavy oil and condense some of the vapors as heavy reflux condensate, collecting the heavy reflux condensate and unvaporized constituents of such heavy oil stock and passing them to a primary fractionating zone in contact with hot vapors therein to vaporize some of the heavy reflux condensate and unvaporized constituents of the heavy oil stock and to condense some of the hot vapors, passing the vapors from the primary fractionating zone to a secondary fractionating zone wherein they are fractionated to separate condensate oil from a light hydrocarbon product adapted for use as a motor fuel, collecting the condensate oil from the secondary fractionating zone and passing it through a cracking zone wherein it is maintained under high temperature and high pressure conditions to effect the desired conversion, collecting the reflux condensate and unvaporized constituents of the heavy oil in the primary fractionating zone and mixing them with cracked products coming from said cracking zone to raise the temperature of the introduced reflux condensate and unvaporized constituents of the heavy oil to a cracking temperature and effect cracking thereof, and passing the commingled treated and cracked products to a separating zone to separate hot

vapors from cracked residue and passing such hot vapors into the primary fractionating zone to supply hot vapors thereto, directing cracked residue from said separating zone to the aforementioned 5 flash tower wherein separation of vapors from tar residue takes place under a lower pressure and the separated vapors pass into the fractionating section thereof into contact with the introduced heavy oil stock, passing the vapors from 10 said fractionating section to a fractionating tower to obtain gas-oil and naphtha fractions, introducing the naphtha fraction into the bottom portion of the secondary fractionating zone and introducing the gas-oil fraction into the top portion 15 of the secondary fractionating zone to effect condensation of heavy constituents of the vapors therein which are added to the condensate oil in the secondary fractionating zone.

8. A process as defined in claim 7 wherein tar residue from the flash tower is passed to a coking zone and at least a portion of the cracked products from said cracking zone is diverted to said coking zone, the cracked products being diverted before admixture therewith of the reflux condensate and unvaporized constituents of the 25 heavy oil.

9. A process for converting higher boiling hydrocarbons into lower boiling hydrocarbons which comprises passing oil as a stream through a primary cracking zone wherein it is maintained under high temperature and high pressure conditions to effect the desired extent of cracking, passing a portion of the stream of resultant cracked products through a secondary cracking zone thence into a separating zone to separate hot vapors from a cracked residue, fractionating the vapors to separate lower boiling hydrocarbons as a product, passing cracked residue thus obtained to a flash zone under a lower pressure for further 30 separation of hot vapors and a tar residue, withdrawing the tar residue and passing it to a coking zone, contacting relatively heavy hydrocarbon oil with cracked vapors from said separating zone to vaporize some of the heavy hydrocarbon oil, 35 admixing unvaporized portions of the heavy oil with the portion of cracked products passing to the secondary cracking zone to thereby raise the unvaporized portions of the heavy oil to cracking temperature, supplying additional heat to the secondary cracking zone to effect cracking of the unvaporized portions of the heavy oil, and 40 passing another portion of the stream of hot cracked products from the primary cracking zone to the coking zone to effect coking of the tar residue introduced into said coking zone.

10. A process for converting higher boiling hydrocarbons into lower boiling hydrocarbons which comprises passing oil as a stream through a cracking zone wherein it is maintained under high temperature and high pressure conditions to effect the desired cracking, passing a portion of the stream of cracked products into a separating zone to separate hot vapors from a cracked residue, passing cracked residue thus obtained to a 45 flash zone under a lower pressure for further separation into hot vapors and a tar residue, withdrawing the tar residue and passing it to an enlarged zone, contacting relatively heavy hydrocarbon oil with the hot vapors from the flash zone to vaporize part of the heavy oil, collecting the unvaporized portions of the heavy oil and contacting them with the hot vapors from the separating zone to vaporize the lighter constituents thereof and condense some of the heavier constituents of 50 the vapors and separating the remaining vapors

as a lower boiling hydrocarbon fraction, collecting and admixing the unvaporized portions of the heavy oil with the portion of the stream of cracked products passing to the separating zone to thereby raise the heavy oil portions to cracking temperature, supplying additional heat to the admixture to effect cracking of the heavy oil portions, and passing another portion of the stream of hot cracked products from the cracking zone to said enlarged zone to effect cracking of the tar 55 residue introduced into said enlarged zone.

11. A process for converting high boiling hydrocarbons into low boiling hydrocarbons which comprises introducing relatively heavy charging stock into contact with hot vapors in a primary fractionating zone, passing vapors from the primary fractionating zone to a secondary fractionating zone wherein fractionation takes place to separate a reflux condensate from lighter fractions, subjecting reflux condensate from the secondary fractionating zone to cracking conditions of temperature and pressure to effect conversion into lower boiling products, dividing the products of conversion into at least two portions, admixing resultant reflux condensate and unvaporized charging stock from the primary fractionating zone with one of the divided portions to supply heat to the heavy oil and to effect cracking thereof, passing resultant products of conversion into a separating zone wherein separation of vapors from residual constituents takes place, passing resultant separated vapors to said primary fractionating zone, subjecting residual constituents derived from said separating zone to further cracking by contacting such residual constituents with the other of the divided portions of the aforesaid products of conversion.

12. A process for converting high boiling hydrocarbons into low boiling hydrocarbons which comprises introducing relatively heavy charging stock into contact with hot vapors in a primary fractionating zone, passing vapors from the primary fractionating zone to a secondary fractionating zone wherein fractionation takes place to separate a reflux condensate from lighter fractions, subjecting reflux condensate from the secondary fractionating zone to cracking conditions of temperature and pressure to effect conversion into lower boiling products, dividing the products of conversion into at least two portions, admixing resultant reflux condensate and unvaporized charging stock from the primary fractionating zone with one of the divided portions to supply heat to the heavy oil and to effect cracking thereof, passing resultant products of conversion into a separating zone wherein separation of vapors from residual constituents takes place, passing resultant separated vapors to said primary fractionating zone, directing resultant liquid residue to a flashing zone wherein the residue is subjected to flash distillation, passing residue from said flashing zone to a coking zone and subjecting the residue therein to coking by contacting it with the other portion of aforesaid products of conversion.

13. A process for converting higher boiling hydrocarbons into lower boiling hydrocarbons which comprises introducing relatively heavy charging stock into a fractionating zone receiving vapors from the flashing zone hereinafter specified, withdrawing resultant reflux condensate and unvaporized charging stock and directing the oil so withdrawn to a primary fractionating zone of the separating zone hereinafter specified, passing vapors from said primary fractionat-

ing zone to a secondary fractionating zone wherein fractionation takes place to separate reflux condensate from lighter fractions, passing resultant reflux condensate from said secondary fractionating zone through a primary cracking zone wherein the condensate is maintained under cracking conditions of temperature and pressure to effect conversion into lower boiling products, withdrawing resultant reflux condensate and unvaporized charging stock from said primary fractionating zone and combining such reflux condensate and unvaporized charging stock with cracked products passing from the primary cracking zone so as to raise the temperature of the admixed reflux condensate and unvaporized charging stock to a cracking temperature and subject such mixture to cracking, passing the resultant treated and cracked products to a separating zone wherein vapors separate from cracked residue, passing resultant separated vapors into said primary fractionating zone, directing resultant cracked residue from the separating zone to the aforesaid flashing zone wherein separation of vapors from residue takes place and from which the vapors pass to the aforesaid fractionating zone of the flashing zone, passing resultant residue from the flash zone to a coking zone and diverting a portion of the high temperature cracked products from the cracking zone to the coking zone to effect coking of the cracked residue introduced thereto, the cracked products being diverted before the introduction into the cracking zone of the reflux condensate and unvaporized charging stock from the primary fractionating zone.

14. A process for converting high boiling hydrocarbons into lower boiling hydrocarbons which comprises introducing relatively heavy charging stock into a fractionating zone receiving vapors from the flashing zone hereinafter specified, withdrawing resultant reflux condensate and

unvaporized charging stock and directing the oil so withdrawn to a primary fractionating zone of the separating zone hereinafter specified, passing uncondensed vapors from said primary fractionating zone to a secondary fractionating zone wherein fractionation takes place to separate a reflux condensate from lower boiling fractions, passing resultant reflux condensate from said secondary fractionating zone through a portion of a cracking zone in a radiant section of a furnace wherein the condensate oil is maintained under cracking conditions of temperature and pressure to effect the desired conversion into lower boiling oils, withdrawing resultant reflux condensate and unvaporized charging stock from said primary fractionating zone and combining such reflux condensate and unvaporized charging stock with cracked products from said radiant section and passing the mixture through another portion of the cracking zone in a convection section of the furnace, directing the resultant commingled and cracked products to a separating zone wherein vapors separate from cracked residue, passing resultant separated vapors into said primary fractionating zone, directing resultant cracked residue from the separating zone to the aforesaid flashing zone wherein separation of vapors from residue takes place and from which the vapors pass to the aforesaid fractionating zone of the flashing zone, passing vapors from the latter fractionating zone to another fractionating zone wherein fractionation is carried on to separate gas oil and naphtha fractions, introducing a naphtha fraction into the lower portion of said secondary fractionating zone, and directing a gas oil fraction into an upper portion of said secondary fractionating zone to effect condensation of constituents therein which are added to the reflux condensate in the secondary fractionating zone.
